(57) **CLAIM**

I claim the ornamental design for a speaker base, as shown and described.

DESCRIPTION

FIG. 1 is a top, front, right side, perspective view of a speaker base showing the new design;

FIG. 2 is a top view thereof;

FIG. 3 is a bottom view thereof;

FIG. 4 is a front view thereof;

FIG. 5 is a rear view thereof; and,

FIG. 6 is a right side view thereof, the left side view being a mirror image of the right side view.

1 Claim, 6 Drawing Sheets

FIG. 1

FIG. 2

FIG. 3

FIG. 4

FIG. 5

FIG. 6
